CLAIM

What is claimed is the ornamental design for a hands-free door opening kit, as shown and described.

DESCRIPTION

FIG. 1 is a front perspective view of the hands-free door opening kit.

FIG. 2 is a front perspective view of the plug for a strike-plate mortise in the hands-free door opening kit.

FIG. 3 is a front view of the plug for a strike-plate mortise in the hands-free door opening kit.

FIG. 4 is a back view of the plug for a strike-plate mortise in the hands-free door opening kit.

FIG. 5 is a bottom view of the plug for a strike-plate mortise in the hands-free door opening kit.

FIG. 6 is a top view of the plug for a strike-plate mortise in the hands-free door opening kit.

FIG. 7 is a right side view of the plug for a strike-plate mortise in the hands-free door opening kit.

FIG. 8 is a left side view of the plug for a strike-plate mortise in the hands-free door opening kit.

FIG. 9 is a front perspective view from above of the hands-free door opener in the hands-free door opening kit.

FIG. 10 is a front perspective view of the hands-free door opener in the hands-free door opening kit.

FIG. 11 is a front view of the hands-free door opener in the hands-free door opening kit.

FIG. 12 is a back view of the hands-free door opener in the hands-free door opening kit.

FIG. 13 is a bottom view of the hands-free door opener in the hands-free door opening kit.

FIG. 14 is a top view of the hands-free door opener in the hands-free door opening kit.

FIG. 15 is a right side view of the hands-free door opener in the hands-free door opening kit; and,

FIG. 16 is a left side view of the hands-free door opener in the hands-free door opening kit.
